UNITED STATES PATENT OFFICE

ARTHUR G. SUTCLIFFE, OF CHICAGO, ILLINOIS, ASSIGNOR TO ILG ELECTRIC VENTILATING COMPANY, OF CHICAGO, ILLINOIS, A CORPORATION OF LOUISIANA

PORTABLE VENTILATING OUTFIT

Original application filed March 19, 1928, Serial No. 262,608. Divided and this application filed May 15, 1930. Serial No. 452,535.

This invention relates to ventilating apparatus, and has reference more particularly to ventilating appliances of a portable character which are adapted for application to the windows of residences and other buildings to expel foul air from the interior or induce fresh air from the outside, without involving any substantial alteration or defacement of the window structure.

10 In an application heretofore filed by me on the 19th day of March, 1928, Serial 262,608, of which this application forms a division, I have disclosed and claimed certain features of the ventilating equipment herein disclosed, comprising a panel adapted to be mounted opposite a window and formed with an opening, a fan motor and fan mounted on said panel over said opening, and a pair of brackets adapted to be attached respectively to members of the window frame with each of the brackets so formed as to engage and hold the panel at both the upper and lower edges of the latter and in combination therewith an extensible telescoping closure strip hinged at 15 its forward edge to the lower edge of the panel and at its rear free edge adapted to rest on the top of the upper sash when the latter is in lowered position; the inner telescoping member of said closure strip being provided 20 on its free edge with a spacer riding on the outer face of the upper sash as the latter is raised and lowered in order to prevent the free edge of the closure strip from striking the top cross bar of the sash as the latter is being lowered.

According to my present invention, I provide on each side of the upper sash a pair of depending push and pull rods, for raising and lowering the upper sash without having to first remove the panel; and these push and pull rods also serve the additional function of guides and spacers for the free edge of the closure strip preventing any interference of the latter with the top stile of the upper sash 25 as the latter is being lowered.

In the accompanying drawings illustrating the practical and preferred embodiment of the present invention—

Fig. 1 is a front elevation of a window frame showing the upper sash lowered and

my improved ventilating outfit applied thereto.

Fig. 2 is a vertical transverse section showing the upper sash in raised position.

Fig. 3 is a vertical transverse section showing the upper sash in lowered position and the free edge of the closure strip resting on the upper cross bar thereof.

Fig. 4 is a vertical section, broken out, in the plane of one of the panel supporting strips.

Fig. 5 is an enlarged perspective detail of the extensible closure strip, showing the under side thereof.

Fig. 6 is a perspective detail of one of a pair of push and pull rods which serve for raising and lowering the upper sash and also as trackways for the free edge of the closure strip.

Fig. 7 is a perspective detail of a bracket 70 detachably engaged by the push and pull rods shown in Fig. 6.

Referring to the drawings 10 designates the top bar and 11 the side bars of a conventional window frame, and 12 and 13 designate 75 respectively the upper and lower window sashes. 14 designates a rectangular panel conveniently made of wood and formed with a central hole 14' in which is mounted an annular frame member 15 formed with radial arms 16 and a ring 17 in which is supported an electric motor 18 operating a direct driven ventilating fan 19 which serves to move air through the ring frame 15 when the upper sash 12 is lowered as shown in Fig. 3.

The panel 14 is supported in working position by means of a pair of metal strips 20 formed on their lower ends with upturned hooks 21 that support the lower edge of the panel, as clearly shown in Fig. 4, and on their upper ends with downturned hooks 22 which overlap the upper edge of the panel. The downturned limb of the hook 22 is formed with an upwardly turned or re-entrant terminal portion 22' that bears against the outer face of the panel 14, and the downturned portion of the hook has a tapped opening to receive a thumb screw 23 which bears against the upturned or re-entrant portion 22' and forces the latter tightly against the panel.

By this means the upper portion of the panel is held tightly against the window frame, and by retracting the thumb screw 23 the panel may be readily entered endwise into, and 5 withdrawn from, its supporting brackets in an obvious manner.

When the upper sash is lowered, as shown in Fig. 3, in order to enable the fan to function efficiently it is desirable to close the opening 10 between the lower edge of the panel and the top of the lowered sash. The panel 14 in practice is made wide enough to serve the widest window of any dwelling or room in which it may be used, and when applied to a 15 narrower window, can overhang the side frame members of the latter, if necessary, without interfering with its proper functioning. The closure strip, however, must be adjustable lengthwise to fit the width of the 20 particular sash with which it cooperates, and for this purpose the closure strip consists preferably, as best shown in Fig. 5, of a sheet metal plate 24 with inwardly folded marginal flanges or lips 25 and 26 on its outer and 25 inner edges respectively. To the outer edge of the strip 24 are secured hinge members 27 that are attached to the lower edge of the panel 14. Slidably engaged with the flanges or lips 25 and 26 of the main panel member 30 24 are adjustable sheet metal extension members 28. Two, or only one, of the extension members 28 may be employed, depending upon the width of the window to be served, and the member or members 28 and the main 35 member 24 are so adjusted that their combined length will equal the width between the sash grooves of the upper sash 12.

When employing a ventilating panel of this character which, when in place, covers 40 the major portion of the upper window sash, it is desirable to provide means for conveniently raising and lowering the upper sash without having to first remove the panel. As 45 a convenient means for this purpose I preferably employ on each side of the upper sash a pair of push and pull rods 30. The upper end of each rod is bent to form a hook 31 adapted to detachably engage with a horizontal U-shaped bracket 32 mounted on the 50 upper end of each sash stile, as shown in Figs. 1, 2 and 3. The vertical limb of the bracket and its upper horizontal limb are provided with holes 33 and 34 respectively (Fig. 6) through which the hook 31 may be successively 55 entered, as clearly shown in Fig. 2. The rod 30, in the closed position of the upper sash, depends somewhat below the lower edge of the panel, as shown in Fig. 2, and may be formed on its lower end with a ring 35 conveniently engaged by the finger. By reference to Fig. 2 it will be observed that the free 60 edges of the extensions 28 of the closure strip ride on the rods 30, thus spacing the free edge of the closure strip from the stiles of the upper sash, preventing any scratching or mar-

ring of the surface finish of the latter and also serving to prevent collision of the free edge of the closure strip with the top bar of the upper sash when lowering the latter. During the lowering of the upper sash the free edge 70 of the closure strip rides on the push and pull rods 30 as shown in Fig. 2, and, as the upper sash reaches its fully lowered position shown in Fig. 3, the free edge of the closure strip rides off the upper ends of the rods 30 and comes to rest on the top cross bar of the lowered sash, in the manner clearly shown in Fig. 3.

In the case of the extensible closure strip herein shown, wherein the extension members 28 are mounted in the guide flanges 25 and 26, the pull rods prevent flange 26 (which is somewhat narrower than the upper sash) from striking against the lower edge of the top stile of the upper sash during the lowering of the latter. However, where a single or 80 unitary closure strip may be employed, the push and pull rods 30 maintain the free edge of the closure strip out of contact with the stiles of the upper sash, preventing, as above 85 stated, the scratching or marring of the surface finish of the latter.

I claim:

1. A portable ventilating appliance of the character described, comprising in combination a panel adapted to be mounted opposite a window and formed with an opening, a fan motor and fan mounted on said panel over said panel opening, means for mounting said panel on the window frame, means for raising and lowering the upper window sash extending downwardly behind said panel, and a closure strip hinged on the lower portion of said panel; the free edge of said closure strip slidably engaging said raising and lowering means and being thereby held out of contact with the upper sash as the latter is lowered and raised.

2. A portable ventilating appliance of the character described, comprising in combination a panel adapted to be mounted opposite a window and formed with an opening, a fan motor and fan mounted on said panel over said panel opening, means for mounting said panel on the window frame, brackets attached to the upper window sash, push and pull rods for raising and lowering the upper sash connected to said brackets and extending downwardly behind said panel, and a closure strip hinged on the lower portion of said panel; the free edge of said closure strip slidably engaging said rods and being thereby held out of contact with the upper sash as the latter is lowered and raised.

3. A portable ventilating appliance of the character described, comprising in combination a panel adapted to be mounted opposite a window and formed with an opening, a fan motor and fan mounted on said panel over said panel opening, means for mounting said

panel on the window frame, brackets attached to the upper window sash, push and pull rods for raising and lowering the upper sash pivoted to said brackets and extending downwardly behind and below said panel, and an extensible closure strip hinged on the lower edge of said panel; the free edges of the end portions of said closure strip slidably engaging said rods and being thereby held out of contact with the upper sash as the latter is lowered and raised.

ARTHUR G. SUTCLIFFE.
